UNITED STATES PATENT OFFICE.

FOREST E. GOODMAN, OF WACO, TEXAS.

DESIGN FOR A STIRRUP.

SPECIFICATION forming part of Design No. 32,254, dated February 20, 1900.

Application filed January 11, 1900. Serial No. 1,154. Term of patent 7 years.

To all whom it may concern:

Be it known that I, FOREST E. GOODMAN, a citizen of the United States, residing at Waco, in the county of McLennan and State of Texas, have invented and produced a certain new and original Design for Stirrups; and I do declare the following to be a full, clear, and exact description of the invention, such as will enable others skilled in the art to which it appertains to make and use the same.

The invention relates to a new and original design for stirrups; and it consists of a stirrup of the shape and configuration shown in the accompanying drawings, in which—

The leading feature of the design resides in a stirrup-body of approximate U shape, the upright side arms a of which are sigmoidally curved and the cross or foot piece b of which is curved longitudinally and arched or convexed laterally and formed with apertures c. 25 The upright arms have on their exterior surfaces longitudinal swells or ribs d, the lower ends of which merge into the surfaces of the arms.

e denotes a tubular cross-piece located between the extreme upper ends of the upright pieces of the U-shaped frame and communicating with apertures f in the upper ends of the upright pieces and provided on its upper side with a longitudinal aperture g. 35

What I claim is—

The design for a stirrup, substantially as herein shown and described.

In testimony whereof I have hereunto set my hand in presence of two subscribing witnesses. 40

F. E. GOODMAN.
